United States Patent Office.

DAVID CUMMING, JR., OF NEW YORK, N. Y., ASSIGNOR TO HIMSELF
AND STEPHEN W. SMITH, OF THE SAME PLACE.

Letters Patent No. 63,707, dated April 9, 1867.

IMPROVEMENT IN CUTTER-HEADS FOR WOOD-MOULDING MACHINES.

The Schedule referred to in these Letters Patent and making part of the same.

TO ALL WHOM IT MAY CONCERN:

Be it known that I, DAVID CUMMING, Jr., of New York, in the county and State of New York, have invented a new and useful Machine for Moulding and Shaping Wood; and I do hereby declare that the following is a full, clear, and exact description of the construction and operation of the same, reference being had to the annexed drawings, making a part of this specification, in which—

Figure 1 is a perspective view.

Figure 2, a horizontal section; and

Figures 3 and 4, vertical sections of a portion of the table, showing the cutter-head in different positions.

The same letters refer to corresponding parts in the different figures, in which—

A is the frame of the machine; B the table; C an upright spindle, having bearings in the frame, and suspended by the swivel D, lever E, and spring F, and rotated in the direction of the arrow by a belt on the pulley G. The spindle is drawn down by the rod H attached to the lever. To the lower end of the spindle is attached the cutter-head K, with the cutters L. M N are guides, attached to the cutter-head, one above and the other below the cutters. The shank of the cutter-head is continued below the lower guide, and enters the bearing O in the table. The bearing O is countersunk to a depth sufficient to allow the lower guide to be depressed below the surface of the table. P is the pattern or shape of the work, to which is attached the piece of wood, W, to be shaped.

In operating, the rod is drawn down and hooked to the pin K, which brings the lower guide a suitable height above the table, as seen in fig. 3. The pattern with the wood attached to it is laid on the table and pressed against the lower guide, when all the superfluous wood is cut off that can be cut one way of the grain. The rod is then drawn down and hooked to the pin S, which depresses the lower guide into the countersink below the surface of the table, as seen in fig. 4. The pattern, with the wood still attached to it, is turned upside down, with the wood resting on the table, and the pattern pressed against the upper guide, when the remainder of the superfluous wood can be cut off with the cutter still rotating in the same direction.

I am aware that wood has been planed and carved to a pattern, a rotary cutter being employed with a guide running against the pattern, so as to determine the shape or form of the article planed. These guides have in some instances been both above and below the cutters, so that the pattern might be on the under or on the upper surface of the wood to be planed. These devices, however, were not adapted to planing with the grain of the wood by the simple inversion of the pattern and wood, because if the cutter had been fitted to run at the level of the bed, (the guide taking the pattern above the wood,) when said pattern and wood were turned over the pattern would come into contact with the cutter. By my improvement this last-named difficulty is obviated by lowering the bed or raising the cutter with facility, so that the planing can be effected continuously by raising or lowering the cutter relatively to the bed, when the pattern and wood are turned over so as to use the guide above or below the cutters interchangeably, according to the position of the pattern. I do not, therefore, claim a rotary cutter held between two heads, which also form guides; neither do I claim the guide and pattern acting below the wood to be planed, nor the guide and pattern acting above the wood to be planed; but what I claim, and desire to secure by Letters Patent, is—

A cutter-head formed with a guide both above and below the cutter, in combination with mechanism for raising or lowering the cutter relatively with the bed, so that the pattern and wood to be planed can be laid either side upwards on the bed, (according to the direction of the grain of the wood in planing,) and the cutter and guides be brought to their proper places relatively to the wood and the pattern, as set forth.

DAVID CUMMING, JR.
